US0D1083033S

(12) **United States Design Patent** (10) **Patent No.:** **US D1,083,033 S**
(45) **Date of Patent:** **** Jul. 8, 2025**

(54) **VALVE**

(71) Applicant: **Linde GmbH**, Pullach (DE)

(72) Inventor: **Douglas Wood**, Edinburgh (GB)

(73) Assignee: **LINDE GMBH**, Pullach (DE)

(**) Term: **15 Years**

(21) Appl. No.: **29/890,216**

(22) Filed: **Apr. 21, 2023**

(30) **Foreign Application Priority Data**

Oct. 26, 2022 (EM) 015001504-0002

(57) **CLAIM**

The ornamental design for a valve as shown and described.

DESCRIPTION

FIG. 1 is a front view of a valve showing my new design; FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

Broken lines depict portions of the valve that form no part of the claimed design.

1 Claim, 7 Drawing Sheets
